UNITED STATES PATENT OFFICE.

ALLAN H. JONES, OF ORANGE, AND ALFRED P. GLASTRE, OF IRVINGTON, NEW JERSEY,
ASSIGNORS TO THE TEA TRAY COMPANY OF NEWARK, N.J., A CORPORATION OF NEW
JERSEY.

HORN-CRANE.

No. 920,957.

Specification of Letters Patent. Patented May 11, 1909.

Application filed March 27, 1907. Serial No. 364,892.

To all whom it may concern:

Be it known that we, ALLAN H. JONES and ALFRED P. GLASTRE, residing at Orange and Irvington, respectively, in the county of Essex and State of New Jersey, both citizens of the United States, have invented certain new and useful Improvements in Horn-Cranes, of which the following is a specification.

The objects of this invention are to secure 10 a horn crane of simple and cheap construction, which can be quickly and readily applied to a talking machine; to secure a construction which shall provide a firm unyielding support for the amplifying horn; to avoid 15 defacement and mutilation of the talking machine cabinet in applying the crane, and to obtain other advantages and results as may be brought out in the following description.

20 Referring to the accompanying drawings, in which like numerals of reference indicate corresponding parts in each of the several figures, Figure 1 shows in side elevation a crane of our improved construction applied 25 to a talking machine cabinet, and Fig. 2 is a similar view of a modified form of the invention; Fig. 3 is a plan of the base piece shown in Fig. 1; Fig. 4 is a detail side view of a certain lever and a portion of its extension piece, as 30 shown in Fig. 1, the lever being partly broken away to show the connection of said parts more clearly, and Fig. 5 shows said lever in plan; Fig. 6 is a side elevation and plan of the extension piece shown in Fig. 2, and 35 Fig. 7 shows in plan and side view the lever of Fig. 2 and its connection to the extension piece.

In said drawings, 1 indicates the box of a talking machine and 2 the usual top plate. 40 Our improved crane as shown in Fig. 1 comprises a base piece 3 having a portion 4 adapted to project beneath the talking machine and providing at its upper part 5 a socket for the horn supporting arm or rod 6 which may be of any suitable or ordinary construction, a set screw 7 holding it in place in its socket. To the side of said base piece 45 next the talking machine is fulcrumed one end of a substantially horizontal lever 8, the other end of said lever being connected to an extension piece 9 adapted to extend upward and hook over the front edge of the top of the talking machine. The said lever is preferably stamped out of sheet metal, as shown

in detail in Figs. 4 and 5, with downwardly 55 turned lateral edges 10, so that a pivotal pin may be passed therethrough to hinge one end to the base piece 3 and the other end to the extension 9. Said extension at its upper end curves inward over the top plate, as at 11, 60 and is preferably provided with a loosely-mounted engaging piece or shoe 12. A clamping screw 13 working in an extension 14 of the base piece is adapted to engage the lever 8 and thus bind against the top of the 65 talking machine the clamping member made up of said lever and the extension piece 9. Obviously the talking machine is thus gripped between the said clamping member and projection 4 of the base piece, and, said 70 base piece also resting upon the table or other supporting surface, a firm and stable support is afforded for the horn supporting means 6. Particularly is this so because the 75 said clamping member engages the top of the talking machine, so that side-wise strain or twisting upon the crane is powerfully resisted. It should also be noted that the talking machine is firmly engaged by the horn crane without marring or biting into its polished cabinet.

Under some conditions, the modified construction shown in Figs. 2, 6 and 7 may be employed, where 15 indicates a base piece having a projection 16 to extend beneath the 85 talking machine and providing at its upper part a socket 17 for the horn supporting arm 18. The sheet metal lever 19 is then apertured intermediate of its ends as at 20 to inclose the upper part of the base piece, 90 a fulcrum pin 21 being then passed through the side flanges 22 of said lever into the base piece. The end of said lever next to the talking machine is then apertured as at 23 to receive the lower end of the extension 95 piece 24, said lower end being upset or otherwise enlarged beneath the lever and the upper end of the extension piece being flattened and bent as at 25 to hook over the top edge of the front wall of the box 1, 100 beneath the top plate 2. The outer end of the lever 19 is threaded to receive a clamping screw 26 which engages the base piece 15 to operate the clamping member.

Obviously other modifications in detail 105 construction could be employed without departing from the spirit and scope of our invention, so long as the upper clamping mem-

ber consists of a pivoted lever and an extension piece adapted to engage the top of the front of a talking machine, said parts being preferably so connected that their angular relations may change.

Having thus described the invention, what we claim as new is:

1. In a horn crane, the combination of a base-piece adapted to project beneath a talking machine, a lever fulcrumed on said base-piece and having an extension adapted to hook over the top of the front side of the talking machine, a clamping screw working in one of said parts and engaging the other, and horn supporting means extending upward from said base piece.
2. In a horn crane, the combination of a base-piece adapted to project beneath a talking machine, a lever fulcrumed on said base-piece, a clamping screw working in one of said parts and engaging the other, an extension piece connected to said lever by a joint permitting their angular relation to change and adapted to hook over the top of the front side of the talking machine, and horn supporting means extending upward from said base-piece.
3. In a horn crane, the combination of a base-piece adapted to project beneath a talking machine, a lever fulcrumed on said base-piece and having an aperture at its end next the talking machine, a clamping screw working in one of said parts and engaging the

other, an extension piece passing through said aperture of the lever and having a lower end which will not pass through said aperture and an upper end adapted to hook over the top of the front side of the talking machine, and horn supporting means extending upward from said base piece.

4. In a horn crane, the combination of a base-piece adapted to project beneath a talking machine, a lever fulcrumed on said base-piece, a clamping screw threaded into one of said parts and engaging the other, an extension piece hinged to the said lever and adapted to engage the talking machine above said base piece, and horn supporting means extending upward from said base piece.

5. In a horn crane, the combination of a base piece adapted to project beneath a talking machine, a clamping member apertured intermediate of its ends to receive the base piece and adapted to engage the talking machine, a clamping screw threaded into one of said parts and engaging the other, a fulcrum pin passing through said clamping member and base piece, and horn supporting means extending upward from said base piece.

ALLAN H. JONES.

ALFRED P. GLASTRE.
